PROJECTING MACHINE

August D. Eitzen, Rockville Centre, N. Y., assignor to News Projection Corporation, New York, N. Y., a corporation of New York

Application September 20, 1932, Serial No. 633,938
Renewed June 9, 1938

9 Claims.

(CL. 88—24)

This invention relates to combined printers and projectors in general and more especially to stock quotation projecting machines for the multiple projection of a single message.

5 Among the objects of the present invention, it is aimed to provide a printer combined with a plurality of projectors for effecting a plurality of projections at right angles to one another through a single strip of tape.

10 It is still another object of the present invention to provide an improved mechanism for expeditiously and effectively assembling and aligning the condensers for a projecting machine head adapted for effecting a plurality of projections 15 at right angles to one another.

15 It is still another object of the present invention to provide a projecting machine head adapted for effecting a plurality of projections through a single strip of tape at right angles to 20 one another and while the tape is disposed in a vertical plane.

20 It is still another object of the present invention to provide a projecting machine head for a projecting machine adapted to effect a plurality of projections at right angles to one another, through a single vertically disposed, horizontally moving strip of tape in association with a vibration dissipating device pivotally mounted to engage the tape before it passes to the light apertures so that the vibrations transmitted thereto by the printer may be effectively ironed out.

25 These and other features, capabilities and advantages of the invention will appear from the subjoined detail description of one specific embodiment thereof illustrated in the accompanying drawings in which—

30 Figure 1 is a plan view partly in section of a projecting machine equipped according to the present invention;

35 Fig. 2 is a plan view on a smaller scale than Fig. 1 and also illustrating the relative position of the screens to the projecting machine;

40 Fig. 3 is a section on the line 3—3 of Fig. 1;

45 Fig. 4 is a perspective of a part of the projection machine showing the vibration dissipating device at the entrance end of the first light aperture; and

50 Fig. 5 is a section on the line 5—5 of Fig. 1.

In the embodiment illustrated, there is preferably provided a base 1 having secured thereon a ticker 2 preferably of the high speed type which has a tape discharge outlet 3 from which the tape T is ejected, passing over the finger 4 and from there down under the finger 5 formed at the end of the lever 6 operatively connected to the automatically operated switch disposed in the housing 7 for controlling the current of the electric motor 8 in the manner now well known with these machines.

55 From the finger 5 the tape passes over the

curved guide 9 which is secured to the side of the housing extension 10. By means of this guide 9, the tape is guided to and between the projections 11 and 12 at the entrance end of the light aperture for the condenser 13. At this entrance end, the tape T passes under the vibration dissipating plate 14 pivoted at 15 to the bracket 16 secured to the cover 17 of the extension 10.

5 Fixed to the plate 14, there is the pin 18 having adjustably mounted thereon a counter-weight 19. The tape engaging end of the plate is provided with three projections 20, 21 and 22 spaced from one another to clear the two rows of printed matter as a rule formed on the tape T by the high speed ticker, such for instance as the 15 row defined by the word "Tape" and the other defined by the number "100".

The light aperture for the condenser 13 designated 23 is formed by an opening cut in the side wall 24 of the extension 10 and the upper end of 20 the light aperture 23 is defined by the flange 25 extending down from the cover 17. From the aperture 23, the tape passes to the tape guides 26 formed at the end of the light aperture 23, which 25 guide consists essentially of projections 27 formed at its upper end and projections 28 formed at its lower end and guide rollers 29 and 30, the 30 guide roller 29 being disposed at the entrance end of the guide adjacent to the light aperture 23 and the guide roller 30 being disposed at the discharge end of the guide.

35 From the roller 30, see Fig. 1, the tape passes to and across the light aperture 31 formed in the wall 32 of the extension 10 to cooperate with the condenser 33.

40 From the light aperture 31, the tape passes to and over the roller 34 at the end of the light aperture 31 secured in the bracket 35 from which the tape passes to and beyond the idler 36 formed on the bracket 37 and then to and over the drive sheave 38 in engagement with which the tape is 45 maintained by the friction roller 39 which is mounted on the lever 40 pivotally mounted at 41 on the bracket 37 and having an abutment 42 which is connected by the spring 43 with the frame 37, resiliently to maintain the friction roller 39 in engagement with the tape T.

45 From the pulling sheave 38, the tape passes to and around the idler 44 and then to the rewind reel 45 mounted on the arm 46 of the bracket 37. The motor 8 is drivingly connected to the pulling 50 sheave 38 and rewind reel 45, the shaft of the motor 8 being provided with a pulley 47 which is connected by the belt 48 to the pulley 49 on the shaft 50 which has formed thereon a worm 51 55 in engagement with the worm wheel 52 mounted on the shaft 53 of the pulling sheave 38.

55 The shaft 53 has also formed thereon a pulley 54 which is connected by the spring belt 55 with the pulley 56 on the shaft 57 of the rewind reel 60

45. The bracket 37 preferably as shown is secured to and mounted on a vertical wall of one of the lamp housing extensions 58.

The lamp housing extension 58 is disposed at 5 right angles to the lamp housing extension 59. The extensions 58 and 59 are substantially rectangular and have their adjacent corners preferably integral with one another as shown in Fig. 1. The triangular space formed between the 10 front ends of the extensions 58 and 59 is preferably provided with a triangular housing 68 having a vertical wall member 68^a extending downwardly therefrom. The extension 10 is substantially rectangular but has two of its opposed corners cut off, the one to form a face flush with the wall 68^a, see Fig. 4, and the other to form the inclined face in alignment with the guide 26. These extensions 58, 59 and 10 and housing 68 are connected to one another to form a composite 15 housing for the projecting machine head.

The wall 24 in which the light aperture 23 is formed is disposed in line with the light rays issuing from the lamp 60 formed in the extension 58, and the light aperture 31 is disposed in position to receive the light rays issuing from the lamp 61. The arrangement of light apertures 23, 31 and lamps 60, 61 respectively, is such that the light rays from the lamps 60, 61 will cross at substantially right angles to one another and the 20 light apertures 23 and 31 as illustrated in Fig. 1 are disposed in planes that are substantially at right angles to one another.

The extensions 58 and 59 are substantially identical with one another, each having a reflector 62 formed in the rear end thereof, a light and heat cut-off shield 63 having an aperture 64 therein disposed between the reflector and the lamp, a pair of condensers 65 and 66 mounted in the housing 67 in front of the lamp to cause the 25 light rays from the lamp 60 or 61 to be directed in parallel rays onto the condenser disposed opposite thereto, in other words, the condenser 13 for the light rays issuing from the lamp 60 and the condenser 33 for the light rays issuing from the lamp 61.

With the arrangement aforesaid, the light rays from two different lamps 60 and 61 that is lamps having different light intensities, may be directed at right angles to one another through a single tape disposed in a vertical plane and passing light 30 apertures that are disposed at substantially right angles to one another, to wit, the light apertures 23 and 31.

The extension 10, see particularly Fig. 4, is 35 much shallower than the lamp housings 58 and 59. This shallow construction serves a particular function in the present instance.

In the present instance, it will be seen, see Fig. 4, that the wall 68^a extends vertically downward 40 from a point just below the level of the upper end of the housings 58 and 59 and from one free corner to the other of such lamp housings 58 and 59. This wall extends down to a level more than 45 one-third of the distance from the upper end of the housing 58 to its lower end.

At this lower end, the wall 68^a is provided with a flange 69 to which is hinged the cover 17 by means of the hinges 70 and 71. Adjacent to the 50 guide 26, there is formed the bracket 72 on which is mounted the pin 73. In the cover 17, there is 55 formed an opening to register with the pin 73 and permit the head 14 of the pin 73 to extend up and above the upper face of the cover 17. On the cover 17, there is pivotally mounted the hook 75

which is adapted to engage the head 14 of the pin 73 and anchor the cover in closed position.

The cover 17 is provided with two short flanges, to wit, the flanges 25 and 76 to form and define the upper edges of the light apertures 23 and 31.

The condensers 13 and 33 are cut to form a face at right angles to their plane faces above or beyond their effective light condensing area. These upper plane faces 77 of the condensers 13 and 33 10 are adapted to cooperate with the cover 17 to determine their position at the light apertures 23 and 31.

To facilitate guiding the condenser 13 in a vertical direction, there are provided lateral guides 15 78 and to provide vertical guides for the condenser 33, there are provided lateral guides 79. For resiliently maintaining the condensers 13 and 33 upwardly in engagement with the cover 17, there are provided the spring arms 80, 80 engaging the 20 condenser 13 below its thickest area to cooperate with the convex face of the condenser 13 to urge it upwardly against the cover 17, and outwardly against the wall 24 and for the condenser 33, there are provided the spring arms 81, 81 for similarly 25 engaging the convex face of the condenser 33 below its thickest area to urge it upwardly against the cover 17, and outwardly against the wall 32.

In turn when the cover 17 is raised, the condensers 13 and 33 may project above their normal 30 level but will be pressed back into their proper position immediately that the cover 17 is closed and secured by the hook 75.

In the present embodiment, it will be seen that the condenser 13 is much thinner than the condenser 33 and is designed for a long focal axis to cooperate with the lenses formed in the housing 82 mounted on the bracket 83 and that the condenser 33 cooperates with the optical lenses formed in the housing 84 mounted on the bracket 40 85, and is designed for a shorter focal axis.

From the foregoing, it will thus appear that irrespective of the variations between the focal axes of the condensers used at the light apertures 23, 31, the spring arms 80, 80 and 81, 81 45 and cover 17 will be effective automatically to position any and all of them.

It would also appear from the foregoing that when it is desired, according to the installation, to have a condenser of a different focal axis than that originally supplied, it will only be necessary to remove the condenser supplied and replace it with the desired one.

It is obvious that various changes and modifications may be made to the details of construction without departing from the general spirit of the invention as set forth in the appended claims.

I claim:

1. A projecting machine having a housing with a vertically extending light aperture, means for guiding a tape in a horizontal direction while in a vertical position across said light aperture, and a vibration dissipating device disposed at the entrance end of said light aperture and consisting of a vertically extending plate pivotally connected at its upper end to said housing and having a tape engaging face on one lateral side thereof below its upper end with the center of gravity of said plate disposed normally to urge said tape engaging face toward the tape, and a counterweight operatively associated with said plate for varying the pressure exercised by said tape engaging face on the tape, said plate and counterweight depending solely upon their weight for engagement with the tape.

2. A projecting machine having a housing provided with a vertically extending light aperture, guiding means at the entrance end and discharge end of the light aperture for a tape, means for drawing the tape while disposed in a vertical position through said guiding means and across said light aperture in a horizontal direction, and a vibration dissipating device consisting of a vertically extending plate pivotally connected to said housing at the entrance end of said light aperture and having a depending tape engaging face below its upper end with the center of gravity of said plate disposed normally to urge said tape engaging face toward the tape, and a counterweight operatively associated with said plate for varying the pressure exercised by said depending face into vibration dissipating engagement with the tape, said plate and counterweight depending solely upon their weight for engagement with said tape.

3. A projecting machine having a housing provided with a vertically extending wall forming a vertically extending light aperture, means for drawing a tape having a plurality of lines of printed matter extending longitudinally of the tape while disposed in a vertical position across said light aperture in a horizontal direction, an abutment having a vertically extending face at the entrance end of said light aperture, a device pivotally connected to said housing and having an interrupted tape engaging face to clear the printed matter, to press the tape against the vertical face of said abutment and yet clear the printed matter formed thereon, and a counterweight associated with said device for urging said interrupted face into vibration dissipating engagement with the tape, said plate and counterweight depending solely upon their weight for engagement with said tape.

4. A projecting machine having a housing provided with two vertically extending walls disposed at right angles to one another, there being a light aperture at the upper end of each wall, a lamp for each light aperture, the lamps being spaced from the light apertures to permit their light rays to cross at right angles to one another while passing to said light apertures, condensing lenses on the inner sides of said walls to cooperate with said light aperture and having their main plane faces in engagement with the inner faces of said walls, said condensing lenses being cut to form secondary plane faces at right angles to their main plane faces, spring fingers for engaging the convex faces of said condensing lenses to urge said condensing lenses against said walls and in an upward direction, a cover flush with the upper ends of said light apertures to engage the secondary plane faces of said condensing lenses and press them into alignment with the upper edges of said vertical walls, and means for anchoring said cover to said housing in said lens alining position.

5. A projecting machine having a housing provided with two vertically extending walls disposed at an angle to one another and having light apertures at their upper ends, a lamp for each light aperture, condensers for the light apertures having their main plane faces in engagement with the inner faces of said walls, said condensers being cut to form secondary plane faces at right angles to said main plane faces, spring fingers for engaging the convex faces of said condensers and pressing them upwardly and toward said walls, a cover pivotally connected to said housing and

adapted to engage the secondary plane faces of said condensers and press them into alinement with the upper edges of said vertical walls, and means for anchoring said cover in such condenser alining position.

6. A projecting machine having a housing provided with two vertically extending walls at an angle to one another, there being light apertures at the upper ends of said walls, condensers of different focal axes, one for each wall, the main plane faces of said condensers engaging the inner faces of said walls, said condensers being cut to form secondary plane faces, spring fingers for engaging the convex faces of said condensers and pressing them upwardly and into engagement with said walls, a cover pivotally connected to said housing and adapted to engage the secondary faces of said condensers to press them into alinement with the upper edges of said vertical walls, and means for anchoring said cover to said housing in such condenser alining position.

7. A projecting machine having a housing provided with two vertically extending walls inclined to one another, there being a light aperture at the upper end of each wall, a lamp for each light aperture, condensing lenses on the inner sides of said walls to cooperate with said light aperture and having their main plane faces in engagement with the inner faces of said walls, said condensing lenses being cut to form secondary plane faces at right angles to their main plane faces, means for engaging the convex faces of said condensing lenses to urge said condensing lenses against said walls and in an upward direction, a cover flush with the upper ends of said light apertures to engage the secondary plane faces of said condensing lenses and press them into alinement with the upper ends of said light apertures, and means for anchoring said cover to said housing in said lens alining position.

8. A projecting machine having a housing provided with two vertically extending walls disposed at an angle to one another and having light apertures at their upper ends, a lamp for each light aperture, condensers for the light apertures having their main plane faces in engagement with the inner faces of said walls, said condensers being cut to form secondary plane faces at right angles to said main plane faces, resilient means for engaging the convex faces of said condensers and pressing them upwardly and toward said walls, a cover pivotally connected to said housing and adapted to engage the secondary plane faces of said condensers and press them into alinement with the upper edges of said vertical walls, and means for anchoring said cover in such condenser alining position.

9. A projecting machine having a housing provided with two walls inclined to one another, there being light apertures at alined ends of said walls, condensers, one for each wall, the main plane faces of said condensers engaging the inner faces of said walls, said condensers being cut to form secondary plane faces, means for engaging the convex faces of said condensers and pressing them into engagement with said walls and in the same direction along said walls, a cover pivotally connected to said housing and adapted to engage the secondary faces of said condensers to press them into alinement with the alining edges of said walls, and means for anchoring said cover to said housing in such condenser alining position.

AUGUST D. EITZEN.
